UNITED STATES PATENT OFFICE.

J. LEEDOM WORRELL, OF PHILADELPHIA, PENNSYLVANIA.

BAG-HOLDER.

SPECIFICATION forming part of Letters Patent No. 323,617, dated August 4, 1885.

Application filed December 1, 1884. (No model.)

To all whom it may concern:

Be it known that I, J. LEEDOM WORRELL, a citizen of the United States, residing at Philadelphia, in the county of Philadelphia and 5 State of Pennsylvania, have invented a new and useful Improvement in Bag-Holders, of which the following is a specification.

My invention relates to an improvement in bag-holders that may be detached from their 10 connections and folded together compactly when not in use for convenience in transportation.

My bag-holder embodies a pair of extended flared arms tenoned to the ends of a cross-brace that separates them, the rear ends of 15 the arms being also tenoned to a clamping-wedge which moves with them, the clamping-wedge being hinged at one edge to the upper end of the front surface of the rear 20 clamping-board that extends downward back of the adjustable standard, to which it is attached. A front clamping-board is connected to the one in the rear by a bracket or supplemental hinge that extends across between 25 their opposing faces, and a flat steel spring in the back of the rear board, whereby, when the holding-arms are turned at right angles to the standard, the clamping-wedge forces the upper end of the clamping-board outward 30 and securely locks the boards upon the standard. The steel spring in the back of the rear board yields sufficiently in accommodation to standards that vary in thickness. A pair of pivoted braces attached to the outer face of 35 the front clamping-board are then turned outward with their upper notched ends resting under the lower surfaces of the bag-holding arms, which prevent said arms being pulled down. These arms are provided upon their 40 surfaces with hooks upon which the edges of the mouth of a bag are placed, and on the lower surfaces of the outer ends of the arms are placed a pair of pivoted hooks to be used when desired to more effectually fasten the 45 mouths of large bags.

My bag-holder also embodies a fixed standard, a series of clamps, rods, and braces drawn together by a semicircular wire spring, whereby the standard is held securely upon the 50 platform of a weighing-scale, as hereinafter more fully described and claimed.

In the accompanying drawings, which make

a part of this specification, Figure 1 is a side elevation of my improved bag-holder in position for the reception of a bag to be filled, and 55 the rods and braces with which it is attached to a platform-scale. Fig. 2 is a front elevation of the same. Fig. 3 is a plan view of the bag-holding devices. Fig. 4 is a plan view of the standards F F', and the clamps, braces, 60 and rods with which they are connected to the platform of a weighing-scale, taken at the line a b of Fig. 2, looking down. Fig. 5 is a vertical section, taken at the line c d of Fig. 2. Fig. 6 is a transverse section of the clamping 65 devices, taken at the line e f of Fig. 2. Fig. 7 is a side view of the bag-holding device, separated from the standard F', the arms K K being in the position they assume when not in use. 70

Like letters of reference in all the figures indicate the same parts.

A is the platform of a weighing-scale. B B' are clamps connected to the edges. C C are braces that have a pivotal connection with 75 said clamps by means of the links a a. They extend across the upper surface of the platform, and are provided with a series of holes, b, with any one of which an end of the semi-circular wire spring D is connected for accommodation to scales of different widths of platforms. The other end of the spring D is connected with a hole in the clamp B', which has the upright brace c back of the standard F and the curved clamps c' c' that connect with 80 the edge of the platform.

E E are wrought-iron rods, the lower ends of which have an eye-connection with the links a a of the clamps B B', their upper ends being bent over to fit into the eyes d d of the 90 standard F. These rods, clamps, and braces are held together by the spring D, and maintain the standard F securely upon the platform.

F' is the upper standard, which is adjustable 95 in its altitudinal position with respect to the standard F. By raising or lowering the standard F', and clamping it by means of the set-screw e within the stationary strips f f and loose strips f' f', different lengths of bags are 100 caused to rest with their bottoms upon the platform A.

G is the back clamping-board, connected to the clamping-wedge g by means of the hinge J.

- H is a like board, secured to the back board, G, by means of the bracket-hinge J', which extends across between the opposing faces of the two clamping-boards.
- 5 I is a flat strip of spring-steel let into the back surface of the board G. It is connected to one side of the bracket-hinge J' by the screws *i i*. Any resilient spring adapted to the purpose may be used.
- 10 The clamping-wedge *g* is rigidly secured by tenons between and to the rear or inner ends of the flared arms K, hereinafter described. It is rounded off throughout its length on the opposite edge of that to which it is hinged to 15 the board G, and serves a double purpose—viz., that of acting as a brace for said flared arms, and also, when said arms are raised to their holding position at right angles to the adjustable standard, (for the attachment of a 20 bag,) its curved or rounded edge forces outward the upper end of the board H, which is hinged in its center to the board G by means of the hinge J'. This action causes a corresponding inward movement of the board or 25 clamp H, and firmly presses it upon the face of the adjustable standard F', securing the two clamping-boards thereon.
- The bracket-hinge J' is composed of two strips of bar-iron of any desired width and 30 thickness. They are of sufficient length to extend across the opposing inner faces of the clamping-boards. The ends of each strip are bent at right angles to the main portion, one of the strips being shorter than the other, so 35 that the bent ends will fit between the opposing ends of the other strip. They are provided with holes through each bent end, whereby they may be confined together by a bolt-nut, allowing a swivel movement of the 40 parts. One of the strips is connected rigidly to the front clamping-board H by means of screws. The other strip or flap of said hinge J' is connected in like manner to the rear board, G, and the spring I. When the arms 45 K are turned at right angles to the standard F', the spring yields slightly, so as not to exert too great a strain upon its connected hinge.
- K K are the bag-holding arms, which have a mortise-and-tenon connection to the ends of 50 the cross-bar *h*, and a like connection with the ends of the clamping-wedge *g*. Said cross-bar *h* is provided on its upper surface with the pointed hooks or pins *k k*, upon which the edge of the mouth of a bag to be filled is 55 placed. At the outer ends and upon the under surfaces of the arms K K are the pivoted hooks *l l*, between which and the arms are placed portions of the edges of the bag, and clamped between them, to more effectually 60 hold large bags in position.
- Attached to the outer surface of the board H by the screws *m m* are the pivoted braces L, notched at their upper ends, which are moved outward and under the arms K K to hold them in their horizontal position. They 65 are seen clearly in Fig. 2 in full lines, the dotted lines showing them moved back when it is desired to allow the arms to drop for the removal of the holder from the standard.
- The mode of connection and operation is as follows: When it is desired to connect the apparatus to a scale for the purpose of filling bags with grain and weighing the contents, the standard F is connected to the platform A by means of the clamp B'. The side clamps, 70 B B, are placed upon the edges and engage therewith. The upper ends of the rods E E are inserted in the eyes *d d* of the standard F. The braces C C are drawn over the face of the platform, and one end of the spring D inserted 75 through a hole in each, holding them together. The other end of the spring is then placed in a hole in the clamp B', thus firmly connecting the parts and securing the standard F in its upright position. The bag-holding device is then placed upon the upper end of the adjustable standard F, the board G on the back, and the board H in front. The arms K K are then turned up to a right angle with respect to the standard, the curved clamping-wedge forcing the upper end of the board H 80 outward, which draws the lower end of said board inward, together with the board G, against the standard, and clamps them securely thereon. The pivotal braces L L then have 85 their upper notched ends turned outward under the arms K K, thus securely locking them in their horizontal position.
- The spring I may be adjusted by means of the screws *i i*, to give sufficient resiliency to 90 permit the clamping-boards to adapt themselves to variations in the thickness of different standards or to the front of a bin or box.
- I claim as my invention and desire to secure by Letters Patent—
1. The bag-holding device consisting of the boards G H, the spring I, hinge J', the arms K K, clamping-wedge *g*, hinge J, and pivoted braces L L, all operating substantially as described, and for the purpose set forth. 95
2. The combination of the clamps B B, having links *a a'*, clamp B', rods E E, screw-eyes *d d*, braces C C, and wire spring E, with the standard F, and the platform of a scale, substantially as described. 100
3. The bag-holder consisting of the boards G H, spring I, hinge J', arms K K, clamping-wedge *g*, hinge J, and braces L L, in combination with the clamps B B B', rods E E, braces C C, and wire spring D, for attachment 105 to the platform of a weighing-scale.

J. LEEDOM WORRELL.
